(57) **CLAIM**

The ornamental design for a purse, as shown and described.

DESCRIPTION

FIG. 1 is a first perspective view of one embodiment of a purse showing my new design.

FIG. 2 is a second perspective view of the embodiment of FIG. 1 deployed in an open configuration.

FIG. 3 is a top perspective view of the embodiment of the purse shown in FIG. 2.

FIG. 4 is a right side elevation view of the embodiment of the purse of FIG. 2.

FIG. 5 is a left side elevation view of the embodiment of the purse of FIG. 2.

FIG. 6 is a front elevation view of the embodiment of the purse of FIG. 2.

FIG. 7 is a rear elevation of the embodiment of the purse of FIG. 2.

FIG. 8 is a top view of the embodiment of the purse of FIG. 2; and,

FIG. 9 is a bottom view of the embodiment of the purse of FIG. 2.

The broken lines shown on the drawing views of FIGS. 1-2 and 4-6 represent stitching and are part of the claimed design.
